H. BAUER

SURFACING TOOL

Filed Nov. 12, 1927

INVENTOR
HUGH BAUER.
By *Attwood & Sles.*
ATTY.

UNITED STATES PATENT OFFICE.

HUGH BAUER, OF SAN FRANCISCO, CALIFORNIA.

SURFACING TOOL.

Application filed November 12, 1927. Serial No. 232,857.

My invention relates to improvements in surfacing tools for evening the surfaces of plastered or tiled walls, and the like.

The primary object of my invention is to provide an improved tool for use in surfacing walls.

Another object is to provide an improved tool which will facilitate the evening of plaster or cement for tiled walls.

10 A further object is to provide an improved tool having a taut wire straight edge to facilitate the smoothing of a plaster or cement wall and the removing of surplus plaster or cement.

15 Another object is to provide an improved tool having a wire straight edge and provided with improved means for maintaining said wire in a straight taut condition.

Another object is to provide an improved 20 tool of the character described having guides whereby the tool may be guided along a molding or other abutment and the wire straight edge positioned in desired spaced relation to the surface of such abutment.

25 A further object is to provide an improved tool of the character described provided with a rigid straight edge bead arranged to engage and even floor surfaces.

A still further object is to provide an improved 30 tool of economical construction and which can be used conveniently and efficiently.

I accomplish these and other objects by means of the improved device disclosed in 35 the drawings forming a part of the present application wherein like characters of reference are used to designate similar parts throughout the specification and drawings, and in which—

40 Fig. 1 is a broken side elevation of my improved surfacing tool;

Fig. 2 is a plan view of the tool as shown in Fig. 1;

Fig. 3 is a left end elevation of the tool, as 45 shown in Fig. 2;

Figs. 4 and 5 are broken sectional views showing different forms of wire supports; and

Fig. 6 is a broken sectional view showing 50 the tile floor evening bead.

Referring to the drawings, the numeral 1 is used to designate in general a body, preferably consisting of a relatively long narrow

strip of wood having parallel longitudinal edges. A wire 2 is mounted in spaced relation to one longitudinal edge of the body 1, one end of said wire being secured upon a rigid support 3 secured upon the end of the body. The other end of the wire 2 is secured to an adjustable support 4 arranged to be 55 operated by a screw 6 and wing nut 7 to stretch the wire taut between the supports 3 and 4. The adjustable support is preferably slidably mounted upon the edge of the body 1 and arranged to be moved relative to a rigid plate 8 secured upon the adjacent end of the body 1 and extending upwardly therefrom to receive the screw 6 and to form an abutment for the wing nut 7. A plurality of supporting posts 9 and 9' are secured 60 at intervals along the edge of the body 1 and arranged to engage and hold the wire 2 in a straight line and prevent displacement of said wire when in service. The posts 9 are apertured and the wire 2 threaded 65 through the apertures, as at 11. The posts 9' are notched at the outer end and the wire 2 received within the notch, as at 12.

A bead 13 is arranged upon the longitudinal edge of the body 1 opposite the wire 2. 70 The bead 13 preferably consists of a metal strip inset into the edge of the body 1 and having an outwardly extending rounded edge forming a straight edge extending substantially the full length of the body 1, said strip being secured by screws 14 or other suitable securing means arranged to rigidly 75 secure the bead.

Guides 16 are adjustably secured upon the 80 ends of the body 1, said guides consisting of metal plates having longitudinally disposed slots 15 arranged to engage threaded posts 17 mounted upon the ends of the body 1. The guides are provided with outwardly turned extensions 18. Wing nuts 19 are 85 threaded onto the posts 17 to lock the guide plates 16 in adjusted positions.

My improved surfacing tool is primarily useful in the laying of tile surfaces. In this connection, the wire straight edge, 90 stretched taut to insure a true straight edge, is applied to the surface of plaster or cement applied roughly to the surface to be tiled, the tool being moved to cause the wire to smooth the surface of the cement and to cut 95 through and remove surplus quantities of 100 105

plaster or cement. By thus cutting through the surplus quantities of cement, the surplus falls away clean without rolling and removing additional quantities of cement or plaster. At the same time an even and substantially smooth surface is obtained onto which tile may be easily and evenly set in the ordinary manner. The slight marks made by the supports 9 and 9' serving to hold the wire 2 against inward or transverse bowing while the wire is being moved across a surface, may be readily smoothed out, if desired, but ordinarily will be covered by the tile.

15 In laying ornamental tile moldings and the like, the edge of the body 1 is applied along the upper edges of such molding, not shown. By tapping the upper edge of the body lightly with a mallet or other suitable 20 tool, the upper edges of the molding tiles may be quickly and accurately aligned and evened. To facilitate this tapping, the wire straight edge 2 is offset from the center of the body 1 to afford adequate surface against 25 which the mallet may strike. The bead 18 is offset from the center in the opposite direction to afford adequate clearance outside of the molding tile to prevent the metal bead from engaging the tiling.

30 In preparing floors and the like for tiling, the bead 18 is utilized for evening the surface of the cement. In this connection, surplus cement is scraped off by resting the bead 18 against the surface of the cement 35 and moving the straight edge formed by said bead and the edge of the body 1 to scrape off the surplus and to smooth the surface. The metal bead 18 lends durability and prevents excessive wear upon the wooden body 40 1 of the tool. At the same time, the metal bead 18 serves to prevent warping of the wooden body.

45 Where moldings, sashes, or other outwardly extending members are present along the edges of the surface to be tiled, the guides 16 are adjusted so that the outwardly extending ends 18 may be applied against such members and moved therealong as a guide, said guides being so positioned that the straight edge wire 2 will be held and guided in the desired spaced relation to the surface of the guiding member. The guides 16 are arranged to be reversed upon the posts 17 to permit their use in connection with the 50 rigid bead 18 when desired.

55 While I have illustrated and described only the preferred embodiment of my invention, the device is, of course, subject to modification in numerous details of construction without departing from the spirit of the invention. I therefore do not wish to restrict myself to the specific form and construction disclosed but desire to avail myself of all modifications which may fall within the 60 scope of the appended claims.

Having thus described my invention what I claim as new and desire to secure by Letters Patent is—

1. A surfacing tool comprising a body; a wire mounted in spaced relation to one edge 70 of the body; and means for stretching the wire taut.

2. A surfacing tool comprising a body; a wire mounted in spaced relation to one edge 75 of the body; means for stretching the wire taut; and a plurality of wire supports mounted upon the body and engaging the wire to prevent displacement of the wire when in service.

3. A surfacing tool comprising a body; a 80 wire mounted in spaced relation to one edge of the body and stretched taut to form a straight edge; and guides mounted upon the body.

4. A surfacing tool comprising a body; a 85 wire mounted in spaced relation to one edge of the body and stretched taut to form a straight edge; and guides adjustably mounted upon the body.

5. A surfacing tool comprising a body; a 90 wire mounted in spaced parallel relation to the edge of the body; means for stretching the wire taut to form a straight edge; supports mounted at intervals along the body and engaging the wire to prevent the same 95 from bowing; and guides mounted upon the body.

6. A surfacing tool comprising a body; a wire mounted in spaced relation to one longitudinal edge of the body, said wire being 100 stretched taut to form a straight edge; and a straight edge bead arranged along the opposite longitudinal edge.

7. A surfacing tool comprising a body having straight parallel longitudinal edges; 105 a wire stretched to form a straight edge in spaced parallel relation to one longitudinal edge of the body; and a bead extending outwardly from the opposite edge of the body, the extreme outer surface of said bead forming 110 a straight edge parallel to the surface of the body edge.

8. A surfacing tool comprising a body; a wire stretched to form a straight edge in 115 spaced relation to one longitudinal edge of the body; and a bead inset into the opposite longitudinal edge of the body and extending outwardly slightly to form a straight edge along the body.

9. A surfacing tool comprising a body; a 120 wire stretched to form a straight edge in spaced relation to one longitudinal edge of the body, said wire being laterally offset from the center line of the body; and a rigid bead arranged upon the opposite longitudinal edge of the body to form a straight edge therealong, said bead being laterally offset from the center line of the body in a direction opposite to the offset of the wire. 125

10. A surfacing tool comprising a body; a wire stretched to form a straight edge in spaced relation to one longitudinal edge of the body, said wire being laterally offset
5 from the center line of the body; and a rigid bead arranged upon the opposite longitudinal edge of the body to form a straight edge therealong, said bead being laterally

offset from the center line of the body in a direction opposite to the offset of the wire; ¹⁰ and guides mounted upon the ends of the body.

In witness whereof, I hereunto set my signature.

HUGH BAUER.
